UNITED STATES PATENT OFFICE.

WILLIAM H. GRINDLEY, OF CONGLETON, ENGLAND, ASSIGNOR TO
WILLIAM S. PITCAIRN, OF NEW YORK, N. Y.

DESIGN FOR EWER.

SPECIFICATION forming part of Design No. 28,144, dated January 11, 1898.

Application filed August 6, 1897. Serial No. 647,378. Term of patent 31 years.

To all whom it may concern:

Be it known that I, WILLIAM H. GRINDLEY, a citizen of Great Britain, residing at Congleton, in the county of Chester, England, have 5 invented a certain new and original Design for a Ewer; and I do hereby declare the following to be a full, clear, and exact description of the same, reference being had to the accompanying drawings, forming a part hereof.

10 In the drawings, Figure 1 is a side view of a ewer embodying my design, and Fig. 2 is a top view and partial section on the plane of the line 2 2 in Fig. 1.

The leading features of my design are as 15 follows:

The body of the ewer A is oblong in shape, projecting forward at a and rearward at a' and laterally at a'' and a''' . Looking at it from the side it is seen to curve downwardly 20 from the lip and inwardly at x from the top, then outwardly at a and a' , and slightly upward at g and g' , and then sharply downward to the base at z and z' , where it turns outward at e and e' to form a flat base provided with 25 irregularly-arranged outward projections, as h , h' , h'' , &c., terminating at the bottom in substantially the same horizontal plane.

The lip of the ewer D is formed of a continuous smooth curve projecting sharply out-

wardly at d , convexly upward at d' , and downward at d'' , whence it sweeps backward to the rear wall d''' of the ewer, where the handle is affixed.

The body of the ewer is divided into panels—on each side a middle panel G and at each 30 end a pair of panels F and F', divided by the medial outside boundary lines f and f' and bounded right and left by the lines g'' and g''' , which gradually lose themselves upward in the body of the ewer. Each side panel G 35 is provided with an embossed ornamentation of leaf-like curved forms j and j' , projecting upward from a central meeting point j' . Similar slightly - embossed ornamentations project upward from the outer edges of the 40 panels F and F'. The handle is composed of curved forms with projecting knobs.

What I claim is—

The design for a ewer substantially as shown 45 and described.

In testimony whereof I have signed this specification in the presence of two subscribing witnesses.

WILLIAM H. GRINDLEY.
